UNITED STATES PATENT OFFICE.

ROBERT F. SCOTT AND PETER MULLEN, OF PHILADELPHIA, PENNSYLVANIA, ASSIGNORS TO EDWIN HARRINGTON, SON AND COMPANY, INCORPORATED, OF PHILADELPHIA, PENNSYLVANIA.

HOISTING MECHANISM.

SPECIFICATION forming part of Letters Patent No. 788,606, dated May 2, 1905.

Application filed December 10, 1904. Serial No. 236,309.

To all whom it may concern:

Be it known that we, ROBERT F. SCOTT and PETER MULLEN, citizens of the United States, and residents of Philadelphia, in the county 5 of Philadelphia and State of Pennsylvania, have invented certain Improvements in Hoisting Mechanism, of which the following is a specification.

This invention has as its leading object the 10 production of an improved hoist that is simple, compact, and durable in construction, having parts that are readily constructed, assembled, and dissociated, and providing, movements that are simple, efficient, and 15 low in the frictional resistance to be overcome in doing the work.

The nature and characteristic features of our improvements will more fully appear by reference to the following description and the 20 accompanying drawings, in illustration thereof, of which—

Figure 1 represents a vertical sectional view taken through the axis of a hoist made in accordance with our invention. Fig. 2 25 represents a side elevation of part of the hand chain-wheel or power-sheave and connections therefor. Fig. 3 represents a side elevation of the mechanism with a casing member removed and a spur-wheel broken to 30 show the gear-train, and Fig. 4 represents a side elevation of the mechanism with parts broken away to show the clutching-gears and parts coacting therewith.

As shown in the drawings, the frame members 35 1 and 2 have journaled in the bearings 1' and 2' thereof the swivel-block 3, which engages the hook 4 to provide a support for the mechanism.

The load-sheave 5 has the hubs 6 and 7 40 projecting therefrom journaled in the respective bearings 8 and 9 of the frame members. On the hub 6, which extends through the bearing 8, is sleeved a spur-wheel 10, which is fixed to the hub and sheave by the key 11. In gear with the spur-wheel 10 are the pinions 12, which are journaled on the spindles 13. The spindles 13 have their inner ends

supported in the bearings 14 of the frame member 1 and their outer ends in bearings 15 of a casing member 16, which coacts with 50 the frame member 1 to incase the gear-train. Fixed to the pinions 12 and revolving therewith on the spindles 13 are the spur-wheels 17, which are in gear with the pinion 18, fixed by a key 19 on the shaft 20.

The shaft 20 passes through and is journaled in the load-sheave 5 and the hubs 6 and 7, fixed thereto, the end of the shaft adjacent to the gear-train being journaled in the bearing 21 of the casing member 16. The opposite end of the shaft 20 extends through the casing member 22, which is fixed to the frame member 2 to incase and support the clutching mechanism. Within the casing member 22 is the frictional clutching-disk 23, having 65 a sleeve 24, which is fixed to the shaft 20 by the key 25, the sleeve extending on the shaft through the casing member. Journaled on the sleeve 24 is a clutch-wheel comprising a hub 26, which extends through and is journaled in the bearing 27 of the casing member, and a disk 28, which frictionally engages or 70 clutches the disk 23 through the leather 29. On the sleeve 24 is a worm 30, which engages the hub 31 of the power-sheave 32, operated 75 by the hand-chain 32'. The movement of the power-sheave inwardly on the worm jams its hub 31 against the clutch-wheel hub 26, forces the disks 23 and 28 into frictional engagement through the leather 29, and thus 80 clutches the power-sheave 32 to the shaft 20. To limit the movement of the power-sheave in the opposite direction, a stop 33 is properly, set on the shaft 20, being fitted to the 85 squared bearing 20' thereof, the sheave having a pin or boss 34 fixed thereto, which is adapted to be engaged by the lug 35 of the stop. The periphery of the clutch-wheel, within which lies the clutch-disk 23, has thereon the teeth 37, which engage with the teeth 38 on a pinion 39, the respective teeth being so inclined and formed that they run together freely in revolving in the directions of the arrows thereon and interlock in the re-

verse action to prevent revolution in the opposite directions.

- The pinion 39 is journaled on a bearing 40, carried by an arm 41, the arm having a hub 42, 5 which is journaled on the extended bearing 9. The arm has a limited rocking movement, its outer part 43 making contact with a shoulder or stop 44, formed in the frame member 2 when the clutching-gears are moving in the 10 direction of the arrows, and when interlocked by the reverse action the pinion 39 is carried into engagement with the stop or dog 45, fixed to the frame member. As the dog is constructed so as to engage the respective 15 teeth 38, when so engaged the pinion 39 is thereby held against rotation reversely to the direction of the arrow thereon and the strain is relieved between the point of the tooth 37 and the crown of the tooth 38, which 20 engage the gears in interlocking relation.

In hoisting, the hand-chain 32' is drawn down to revolve the power-sheave 32 inwardly on the worm 30, causing the hub 31 to jam the hub 26 and the disk 28 to clutch 25 the disk 23, whereby the power-sheave is fixed to the shaft 20 and the latter revolved. The revolution of the shaft 20 and the pinion 18, fixed thereon, revolves the spur-wheels 17 and the pinions 12, the latter revolving the 30 spur-wheel 10 and the sheave 5 to lift the load carried by the chain 5'. Upon withdrawing the power from the hand-chain 32' the load on the chain 5' acts to revolve the load-sheave, the gear-train, and the shaft in 35 the reverse direction, whereby the screw 30 acts to draw the power-wheel hub 31 against the clutch-wheel hub 26 and hold the disks 23 and 28 in frictional engagement. As the clutch-wheel is held by the interlocking of its 40 teeth 37 with the teeth 38 of the clutch-pinion, the load is held stationary until elevated in the manner already described or lowered by revolving the power-wheel outwardly on the worm, so as to relieve the pressure between the friction-disks and permit the load 45 to run down. The rate of lowering of the load is regulated to the speed of the power-sheave by the action of the load in feeding the screw through the sheave to tighten the 50 clutching-disks, and the reversal of the power-sheave, so as to drop or too rapidly lower the load, is prevented by the limiting action due to the engagement of the boss 34 with the lug 35.

Having described our invention, we 55 claim—

- 1. A hoisting mechanism comprising a sheave, an externally-toothed spur-wheel fixed to said sheave, a shaft extending 60 through and revolving in said sheave and wheel, a pinion fixed to said shaft, a spur-wheel engaging the pinion fixed to said shaft, and a pinion fixed to said last-named spur-wheel and engaging said first-named spur-wheel, substantially as specified.

2. A hoisting mechanism comprising a frame, a sheave having hubs journaled in said frame, an externally-toothed gear-wheel fixed to one of said hubs, a shaft extending through and journaled in said sheave, a gear-wheel fixed to said shaft, and a pair of gear-wheels fixed together and engaging the respective gear-wheels fixed to said hub and shaft, said pair of gear-wheels having an axis of rotation stationary with reference to said frame, substantially as specified. 75

3. A hoisting mechanism comprising a pair of frame members, a revolute sheave carried by said frame members, an externally-toothed gear-wheel fixed to and revolving with said sheave, a shaft passing through and revolving in said sheave and gear-wheel, a gear-wheel fixed to said shaft, a pair of gear-wheels fixed together and engaging respectively the gear-wheels fixed to said 85 sheave and shaft, an incasing member coacting with one of said frame members to inclose said gear-wheels, and bearings for said pair of gear-wheels in said last-named frame and incasing members, substantially as specified. 90

4. A hoisting mechanism comprising a sheave, a journal fixed to said sheave, an externally-toothed gear-wheel fixed to said journal, a frame member having a bearing for said journal between said sheave and wheel, a casing member joined to said frame member, a shaft passing through and revolute in said sheave, journal and gear wheels, said shaft having a bearing in said casing member, a gear-wheel fixed on said shaft, 100 and a plurality of pairs of gear-wheels supported by bearings on said frame and casing members, the gear-wheels of each pair engaging respectively the gear-wheels fixed to said journal and shaft, substantially as specified. 105

5. A hoisting mechanism comprising a frame member having a bearing, a load-sheave having a hub journaled in said bearing, a shaft passing through and revolute in said sheave and hub, a clutch member having a sleeve with a screw thereon fixed on said shaft, a clutch member having a hub journaled on said sleeve, a casing member having a bearing in which said clutch-member hub is journaled, a power-sheave engaging said screw and clutch-hub, and gearing connecting said shaft and load-sheave, substantially as specified. 110 115

6. A hoisting mechanism comprising a frame member having a bearing, a load-sheave having a hub journaled in said bearing, a shaft passing through and revolute in said sheave, a frictional clutching-disk having a sleeve with a screw thereon fixed to said shaft, a toothed clutching-wheel on said 125 sleeve and having a frictional member coacting with said frictional disk, a power-sheave engaging with said screw for moving said clutching-wheel on said sheave, an arm carried by and oscillating on the bearing of said 130

frame member, a toothed wheel carried by said arm and engaging the teeth of said clutching-wheel, and a dog for engaging the wheel carried by said arm, substantially as specified.

7. A hoisting mechanism comprising a frame member having a bearing, a lifting-sheave revolubly supported by said bearing, a revoluble shaft journaled in said sheave, 10 gearing connecting said shaft and sheave, an arm rocking on said bearing, a wheel carried by said rocking arm, a second wheel adapted to be engaged and held by said first wheel, and mechanism for holding said first wheel, 15 substantially as specified.

8. A hoisting mechanism comprising a frame member having a bearing extending therefrom, a load-sheave journaled in said bearing, a shaft journaled in said sheave, 20 gearing connecting said shaft and sheave, an arm rocking on said bearing, a revoluble pinion carried by said arm, a revoluble gear-wheel engaged by said pinion, a stop on said frame member for limiting the movement of 25 said arm in one direction, and a dog on said frame member for engaging and holding said

pinion when said arm is moved in the opposite direction, substantially as specified.

9. A hoisting mechanism comprising a frame, a load-sheave revolubly supported by 30 said frame, a shaft journaled in said sheave, mechanism whereby said shaft operates said sheave, a frictional disk fixed to said shaft, a wheel revoluble relatively to said disk and having a frictional member coacting therewith, said wheel having inclined teeth thereon, a rocking arm, a pinion journaled on said rocking arm, and oscillating in a circle concentric with said wheel, said pinion having inclined teeth which roll in one direction and 35 interlock in the other direction with the teeth on said wheel, and a dog for engaging said pinion, substantially as specified.

In testimony whereof we have hereunto set our hands, this 7th day of December, 1904, 40 45 in the presence of the subscribing witnesses.
